UNITED STATES PATENT OFFICE.

NORMAN HOWARD CAUFIELD, OF VICTORIA, BRITISH COLUMBIA, CANADA.

STOOKING-MACHINE ELEVATOR.

Application filed November 10, 1922. Serial No. 600,163.

To all whom it may concern:

Be it known that I, NORMAN HOWARD CAUFIELD, a subject of the King of Great Britain, and a resident of the city of Victoria, in the Province of British Columbia, Canada, have invented certain new and useful Improvements in Stooking-Machine Elevators, of which the following is a specification.

10 My invention relates to improvements in stooking machine elevators, and the object of my invention is to provide a device of this character by means of which the sheaves may be transferred from the binder to the stooker automatically and in a simple, practical, and highly efficient manner. A further object is to provide for the automatic stoppage of the device when the stooker basket is loaded and dumping and its automatic restarting to load the basket after dumping.

I attain these objects by the construction illustrated in the accompanying drawings in which—

25 Fig. 1 is a side elevation of the elevator in assembled position.

Fig. 2 is a plan view of Fig. 1.

Fig. 3 is a side elevation of the elevator starting and stopping clutch.

30 Fig. 4 is an end view of Fig. 3.

Similar figures of reference indicate similar parts throughout the several views.

While the device now to be described may be applied to other stooking machines it is 35 primarily intended to be used in combination with the machine fully described and illustrated in my pending application for Letters Patent of the United States filed June 2nd, 1922, under Serial No. 565,347, to 40 which reference may be had if desired.

In the present drawings 1 indicates the horizontal U-shaped frame of the stooking machine structure provided on the side nearest the binder with the traction wheel 2 to 45 which is secured a sprocket 3 chain-connected to a sprocket 4 rotatably mounted on a shaft 5 rotatably mounted in a bearing 6 secured to the frame and this sprocket 4 is provided with a clutch 7 and is capable of being engaged to the shaft 5 to rotate the same by means of suitable mechanism associated with the clutch 7, a full description of which will be found in the application Serial No. 565,347, on page 3. For the purpose of this present specification, however, 50 it will only be necessary to understand that

the shaft 5 starts to rotate concurrently with the setting in motion of the stooker basket and continues to rotate throughout the complete basket movement.

Rotatably mounted in bearings 8 and 9 mounted on a frame 10 rigidly secured to the stooker frame 1 between it and the binder is a shaft 11 which extends at right angles to the stooker, which shaft is provided at the 60 stooker end with a loose sprocket 12 around which the chain 13 passes, this chain being one which connects the stooker sprockets 3 and 4, from which it will be seen that the sprocket 12 rotates concurrently with 70 sprockets 3 and 4.

The outer, or binder, end of the shaft 11 is provided with a bevel gear 14 meshing with a bevel gear 15 secured to the end of a shaft 16 rotatably mounted in bearings 75 17 and 18 secured to the frame 10, which shaft extends at right angles to the shaft 11 and is parallel to the stooker frame.

Secured to the shaft 16 adjacent its opposite ends are sprockets 19 and 20 around which 80 are passed endless link-belt chains 21 and 22, these chains being inclined upwardly and extending to a point above the level of the stooker basket and slightly beyond the inner side plate 23 of the basket, the inner and outer side plates of the basket being indicated

in this case by the numerals 23 and 24, and the bottom plate by the numeral 25. The chains at their upper ends are passed over sprockets 26 and 27 secured to a shaft 28 90

rotatably mounted in bearings 29 and 30 erected on and secured to the stooker frame. Extending between and connecting the chains together at suitably spaced intervals are transverse slats 31, 32, and 33, each of 95 which slats is provided with a plurality of hooks 34, from which it will be seen that a conveyor or elevator is formed by the chains, slats, and hooks and that, as the lower end of this elevator lies in close proximity to the binder platform, indicated by the numeral 35, sheaves delivered on to the platform will be caught by the moving hooks and carried up to be discharged at the upper end of the elevator into the stooker basket.

100 In order to provide for the automatic stopping of the elevator just described when the basket is dumping and its automatic restarting to load the basket again after emptying the loose sprocket 12 on the shaft 11 105 is provided on its outer face with the female portion 36 of a jaw clutch, the male por-

110

tion 37 of which is slidably connected to the shaft and rotatable with it, and between the outer end of this male clutch portion and a collar 38 spaced apart from it, the collar 5 being secured to the shaft, is a coil spring 39, as shown. A clutch lever 40 is provided the lower end of which is disposed in the groove of the male clutch portion while its upper end is connected to a crank 41 secured to the outer end of the stooker shaft 5 on the stooker. The lower end 42 of the clutch lever is tapered on one side so that a wedge 43 is formed the taper of which is complementary to the taper of the face 15 of a collar 44 seated in the clutch groove, and the tapered face of the wedge 43 moves on the face of the collar 44, that is, it is normally in contact with it, during operation, which is as follows: The sheaf-receiving basket of the stooker, indicated generally by the letter A, being empty and in the receiving position, the clutch is in engagement so that the shaft 11 rotates thus rotating shaft 16 and operating the elevator 20 to elevate the sheaves from the binder and drop them into the basket. The crank 41 is then at the bottom of its down stroke and consequently the wedge 43 is also at the lowest point of travel, the thick end 30 being downmost, as shown in Fig. 1. As soon as the stooker basket is full it is set in motion to effect tilting and dumping in the manner described in the application hereinbefore referred to, Serial No. 565,347, 35 so that the crank 41 commences rotating, since shaft 5 then rotates. On the upstroke of crank 41 the clutch lever and wedge 43 are drawn upwardly so that the male clutch portion 37 is moved away from the female portion until when the crank reaches the end of its upstroke, which is coincident with the arrival of the basket in the dumping position, the male clutch portion is fully 40 disengaged from the female portion and the shaft 11 ceases rotation, with consequent stoppage of the elevator. The spring 39 is then under tension. The shaft 5 and crank 41 continuing to rotate the clutch lever is then moved downwardly, depressing the wedge, so that the male portion of 45 the clutch is gradually moved into re-engagement with the female portion by the spring 39 so that when the basket arrives at the sheaf-receiving position again the conveyor is operating and the clutch fully 50 re-engaged, while the hooks 34 are so positioned that the re-delivery of the sheaves into the basket is commenced in the minimum of time after commencement of the 55 elevator operation.

From the foregoing it will be seen that I have provided a simple elevating device for transferring sheaves from the binder to the stooker, which is highly efficient and of great utility.

What I claim as my invention is:—

1. The combination with a stooking machine, having a basket tiltable from a sheaf-receiving position to a dumping position and returnable to the normal sheaf-receiving position, the operating mechanism thereof, and a binding machine, of a sheaf-elevator disposed between the stooker and the binder, said elevator comprising travelling chains extending from the binder sheaf-delivery platform to a point above the level of the stooker basket, said chains being provided with hook members adapted to engage under a sheaf on the said platform, mechanism for operating said chains, a continuously operating sprocket included in the stooker operating mechanism, and means for connecting said sprocket and the chain operating mechanism when the basket is in the normal sheaf-receiving position and for disconnecting them when the basket is in the dumping position. 70

2. The combination with a stooking machine, having a basket tiltable from a sheaf-receiving position to a dumping position and returnable to the normal sheaf-receiving position, the operating mechanism thereof, and a binding machine, of a sheaf elevator disposed between the stooker and the binder, said elevator comprising travelling chains extending from the binder sheaf-delivery platform to a point above the level of the stooker basket, said chains being provided with hook members adapted to engage under a sheaf on the said platform, mechanism for operating said chains, a continuously operating sprocket included in the stooker operating mechanism, and means for connecting said sprocket and the chain operating mechanism when the basket is in the normal sheaf-receiving position and for disconnecting them when the basket is in the dumping position. 80

3. The combination with a stooking machine, the operating mechanism thereof, and a binding machine, of a sheaf elevator disposed between the stooker and the binder, said elevator comprising a rotatably mounted shaft extending at right angles to the stooker provided adjacent the stooker end with a 95

a sliding male clutch portion and at its opposite end with a bevel gear, a transverse shaft rotatably mounted in close proximity to the binder sheaf-delivery platform having a bevel gear in mesh with the gear aforesaid, a pair of sprockets secured to said transverse shaft towards each opposite end thereof, a shaft rotatably mounted on the stooker frame above the level of the basket parallel to the said transverse shaft and having a pair of sprockets secured thereon towards each opposite end thereof and in alignment respectively with the transverse shaft sprockets, a chain passed around each pair of sprockets, spaced slats connecting 100

110

115

120

125

130

135

the chains each slat being provided with hook members adapted to engage under a sheaf on the said binder platform, a continuously operating sprocket included in
5 the stooker operating mechanism provided with an integral female clutch portion complementary to the male clutch portion aforesaid and engageable therewith, and means for connecting and disconnecting said male
10 and female clutch portions.

4. The combination with a stooking machine, the operating mechanism thereof, and a binding machine, of a sheaf elevator disposed between the stooker and the binder,
15 said elevator comprising a rotatably mounted shaft extending at right angles to the stooker provided adjacent the stooker end with a slidable male clutch portion and at its opposite end with a bevel gear, said
20 shaft having a collar secured thereto spaced behind the clutch and a spring between the clutch and the collar, a transverse shaft rotatably mounted in close proximity to the binder sheaf-delivery platform having a bevel gear in mesh with the gear aforesaid, a pair of sprockets secured to said transverse shaft towards each end thereof, a shaft rotatably mounted on the stooker frame

above the level of the basket parallel to said transverse shaft and having a pair of 30 sprockets secured thereon towards each opposite end thereof and in alignment respectively with the transverse shaft sprockets, a chain passed around each pair of sprockets, hooks carried by said chains adapted to engage under a sheaf on the said platform, a continuously operating sprocket included in 35 the stooker operating mechanism provided with an integral female clutch portion complementary to the male clutch portion aforesaid and engageable therewith, a crank included in the stooker operating mechanism and operative concurrently therewith, and a clutch lever connected at one end to said crank and having its opposite end formed as 40 a wedge shaped jaw engaging in the groove of the said male clutch portion whereby movement of the jaw in opposite directions permits respectively engagement of the male clutch portion and the female clutch portion 45 under extension of the said spring or disengages them.

In testimony whereof I affix my signature at Victoria, B. C., Canada, this 30th day of October, 1922.

NORMAN HOWARD CAUFIELD.
